[57] CLAIM

The ornamental design for a combined bottle and closure for cosmetic products, as shown and described.

DESCRIPTION

FIG. 1 is a side elevational view of a combined bottle and closure for cosmetics, showing my new design, the side opposite that shown in FIG. 1 being the mirror image thereof except for the absence of the oval outline at the top of FIG. 1.

FIG. 2 is a side elevational view thereof, the side opposite that shown in FIG. 2 being the mirror image thereof; FIG. 3 is a top plan view thereof; and, FIG. 4 is a bottom plan view thereof.
